METALWORKING TOOLS—MEANS FOR
CONNECTING THE CUTTER TO THE
HOLDEREmil Gairing, Detroit, Mich., assignor to The
Gairing Tool Company, a corporation of
Michigan

Application June 27, 1936, Serial No. 87,727

8 Claims. (Cl. 279—93)

My invention relates to metal working tools, and particularly to the means for connecting the cutter to the holder.

In the accompanying drawings:—

Figure 1 is a plan view of the assembled tool adjacent to the driving lugs, the upper wall of the holder and one of its driving lugs and the upper portion of the locking pin being cut away as indicated in Figure 2, by the straight lines 1—I—I, and an arcuate line joining their inner ends.

Figure 2 is a cross-section of a milling tool embodying my invention taken through the driving lugs at right angles to the axis of the tool.

Figure 3 is a plan and sectional view of the assembled tool, taken on or about the broken and straight arcuate lines III—III, of Figure 4.

Figure 4 is a cross-sectional view, similar to Figure 2, showing the parts in another relative position.

Figure 5 is a detail cross-sectional view through the shank and lugs of the cutter,—removed from the holder.

Figure 6 is a plan view showing the shank of the cutter, which fits into a corresponding socket in the holder.

Figure 7 is a detail section of a part of the wall of the holder showing the locking pin and its operating mechanism.

Figure 8 is a detail view of a portion of the wall of the socket of the holder looking outwardly as indicated by the arrows, showing the shape of the slot in which the locking pin reciprocates lengthwise of the tool.

The numeral 2 denotes the holder having the usual cavity or socket, shaped to receive and co-act with the shank of the cutter. The numerals 3—3—3 are driving lugs extending inwardly from the wall of the holder at an angle of 120° to each other.

The numeral 4 designates the cutter provided with outwardly extending lugs 5—5—5, angularly spaced 120° apart and adapted to come between the lugs 3—3—3, when engaged in the holder.

The lugs 3 and 5 are rectangular in cross-section,—have radial faces,—and are of a circumferential extent that will permit considerable free relative movement of rotation.

The numeral 6 denotes a cavity extending inwardly from the middle of a driven face of each of the lugs 5, and 6^a designates an offset at the inner end of said cavity on the side toward the inner end of the socket of the holder.

The numeral 7 indicates a slot extending radially into the wall of the socket of the holder but not through said wall, and the numeral 8,

a bore extending into the wall of the holder from the edge at its outer end, and parallel to the axis thereof. The axis of the bore intersects that of the slot 7, at right angles.

The numeral 9 denotes a smaller bore coaxial with the bore 8, extending radially from the cavity 7, opposite to the bore 8.

The cavity 7 is semicircular at its ends and is longer than wide, as shown most distinctly in Figure 8.

The numeral 10, denotes a pin fitting adapted to reciprocate longitudinally in the slot 7, and extends radially into the socket of the holder. The pin has a transverse aperture formed therethrough as shown in broken lines in Figure 8.

The numeral 11 indicates a pin having a head 11^a, adapted to fit and slide in the bore 8, and a shank 11^b passing through the transverse aperture in the pin 10 and into, but not to the end of, the bore 9. The numeral 12 denotes a coil pressure spring in the bore 8, the numeral 12^a denotes a screw-threaded plug in the outer end of the bore 8, acting to produce a resilient pressure through the spring 12 upon the head 11^a of the pin 11; pressing said head against the pin 10 and forcing the latter toward the inner end of the slot 7.

To form the slot 7, a sufficient opening is first made through the opposite holder-wall as indicated by broken lines in Figure 2, and the tool for forming said slot is passed through said opening, which opening is subsequently closed and the closure becomes an integral part of the wall.

The pin 10 is so located between a pair of lugs 3—5 normally, that a part of its wall is a little further into the socket of the holder than the inner portion of the offset 6^a, but so that a side wall of said cavity may strike its rounded portion to force said pin outward in the slot 7, when said pin may enter said cavity and be forced against the inner wall of the offset 6^a, to hold the cutter in position in the holder. In this position the pin 10 also holds the cutter from accidental rotation.

To adjust the cutter into the holder its shank 45 is inserted axially in the holder, the lugs 5 passing between the lugs 3 and one of said lugs between a lug 3 and the inner end of the pin 10 as shown in Figure 1. The holder and cutter are then relatively rotated until the radial faces of the lugs 3 and 5 come into driving contact. During this rotation the wall of the cavity 6 engages the pin 10 and presses it outward till it enters the mouth of said cavity and when said pin is opposite 55

the offset 6^a, it is forced into the same by the action of the spring 12.

The pin 10 is adapted to reciprocate freely on the shank 11^b of the pin 11.

5. What I claim is:

1. The combination of a holder having a lug extending inwardly from the wall of its socket; a cutter having a lug extending outwardly adapted to engage said first mentioned lug, a pin extending inwardly from the wall of said holder movable in the direction of the length of said holder, a slot extending inward from the edge of the lug on the cutter that shall engage the lug on the holder, said pin being adapted to enter said slot when the lug on the cutter moves into engagement with the lug on the holder.

2. The combination of a holder having a lug extending inwardly from the wall of its socket; a cutter having a lug extending outwardly adapted to engage said first mentioned lug; a pin extending inwardly from the wall of said holder movable in the direction of the length of said holder, a slot extending inward from the edge of the lug on the cutter that shall engage the lug on the holder and having an offset at its inner end, said pin being adapted to enter said slot and engage in said offset when the lug on the cutter moves into engagement with the lug on the holder; and a spring acting to press said pin toward the inner end of the holder socket.

3. The combination of a holder having a lug extending inwardly from the wall of its socket; a cutter having a lug extending outwardly adapted to engage said first mentioned lug; a pin extending inwardly from the wall of said holder movable in the direction of the length of said holder, a slot extending inward from the edge of the lug on the cutter that shall engage the lug on the holder and having an offset at its inner end, said pin being adapted to enter said slot and engage in said offset at its inner end, said pin being adapted to enter said slot and engage in said offset when the lug on the cutter moves into engagement with the lug on the holder; and a spring acting to press said pin toward the inner end of the holder socket and against the inner wall of said offset.

4. The combination of a holder having a lug extending inwardly from the wall of its socket; a cutter having a lug extending outwardly adapted to engage said first mentioned lug; a longitudinal slot in the wall of said holder; a pin in said slot extending into the holder socket and adapted to reciprocate longitudinally of said slot; a spring adapted to press said pin in the direction of the inner end of said slot; a slot extending inward from the edge of the lug on the cutter that shall engage the lug on the holder and having an offset at its inner end, said pin being

adapted to enter said slot in the lug extending from the cutter and be forced into said offset by said spring and against the wall of said offset.

5. The combination of a holder having a lug extending inwardly from the wall of its socket, a cutter having a lug extending outwardly, adapted to engage said first mentioned lug; a longitudinal slot in the wall of said holder; a bore in the wall of said holder extending from the outer edge of said wall into said slot; a pin in said slot extending into the holder socket adapted to reciprocate longitudinally in said slot; a spring in said bore engaging said pin under compression, a slot extending inward from the edge of the lug on the cutter that shall engage the lug on the holder and having an offset at its inner end, said pin being adapted to enter said slot in the lug extending from the cutter and be forced into said offset by said spring and against the wall of said offset.

6. The combination of a holder having a lug extending inwardly from the wall of its socket; a cutter having a lug extending outwardly, adapted to engage said first mentioned lug; a pin extending inwardly from the wall of said holder movable in the direction of the length of said holder, a slot extending inward from the edge of the lug on the cutter that shall engage the lug on the holder and having an offset at its inner end, said pin being adapted to enter said slot and engage in said offset when the lug on the cutter moves into engagement with the lug on the holder; and a spring acting to press said pin toward the inner end of the holder socket, a wall of said slot being adapted to engage said pin and force it into position to enter said slot.

7. In an apparatus of the kind described, a holder; a slot extending from the socket of said holder into the wall thereof; a pin adapted to reciprocate laterally in said slot, a bore extending in the direction of reciprocation of said pin and opening into said slot; said pin having a transverse aperture therethrough; and a second pin adapted to reciprocate in said bore and extending into said aperture.

8. In an apparatus of the kind described, a holder; a slot extending from the socket of said holder into the wall thereof; a pin adapted to reciprocate laterally in said slot; a bore extending in the direction of reciprocation of said pin and opening into said slot, said pin having a transverse aperture therethrough; and a second pin adapted to reciprocate in said bore and extending into said aperture; and a pressure spring in said bore acting upon said second pin, said second pin being adapted to engage the first mentioned pin to actuate the same in the direction of action of said spring.

EMIL GAIRING.
